CONNECTOR PLUG

Stanley J. Wyglendowski, South Orange, N. J.

Application May 27, 1947, Serial No. 750,745

2 Claims. (Cl. 173—361)

1

This invention relates to a connector plug, particularly to a connector plug adapted to provide a connection to standard household power outlets of the prong receiving type.

Connector plugs of the type to which the invention relates commonly project for a distance of the order of an inch from the surface of the receptacle providing the power outlet. Even where such receptacles are flush with the wall of the room served by the outlet, the plugs project into the room for a sufficient distance to render it likely to be accidentally displaced by persons in the room, and occasionally to be broken.

It is among the objects of the present invention to provide a connector plug of the type described which will lie flat against the surface of the receptacle, and will project no more than half an inch therefrom.

It is a further object of the invention to provide a connector plug in which the cable outlet opening extends at right angles to the prongs so that a pull upon the cable does not readily disengage the plug from the socket.

It is a further object of the invention to provide a plug of the type described which may be readily assembled and disassembled to the end that the same will be compact, simple to manufacture, and may be readily disassembled for repair or connection to new cables.

The attainment of the foregoing and other objects and features of the invention will be made fully apparent to those skilled in the art from a consideration of the following detailed description taken in conjunction with the accompanying drawing in which:

Figure 1 is a front elevation of a connector plug constructed in accordance with the invention;

Figure 2 is a section taken on the line 2—2 of Figure 1;

Figure 3 is a front view partially broken away with parts omitted;

Figure 4 is a perspective view of one of the prongs of the plug;

Figure 5 is a view similar to Figure 4 showing a modified form of the prong; and

Figure 6 shows a perspective view of a modified form of the plug with the cable attached.

Referring more particularly to the drawing wherein like reference numerals refer to like parts throughout, an electrical plug generally indicated by reference numeral 11 comprises a square shaped receptacle 10 fabricated of insulating material and having its top open. A solid post 28 also fabricated of insulating ma-

2

terial is positioned within said receptacle 10 substantially centrally thereof and has one end fixedly secured to the bottom of said receptacle. The other end of said post terminating at a point spaced inwardly from the open top of the receptacle is cut away inwardly from the other end and extending completely therearound to form a ledge 50. The bounding wall of said receptacle is cut away inwardly from the open top and completely around said receptacle to form a second ledge 20. The first and second ledges are in alignment with each other and extend above the bottom equal heights. A flange 51 projects from the bounding wall of said receptacle adjacent the open top and extends completely therearound.

A first prong 16 fabricated of conductive material has a flat head 18 on one end thereof positioned on one side of said post and extends through the open top of said receptacle. The head 18 rests against the adjacent portions of said first and second ledges 50 and 20 respectively. A second prong 17 fabricated of conductive material also has a flat head 19 on one end positioned on the other side of said post and extends through the open top of said receptacle with its head resting against the adjacent portions of said first and second ledges. A passage 25 branches into passages 27 and 26 and extends inwardly from one side of the said receptacle for receiving a cable such as 43.

A cover plate 13 fabricated of insulating material surrounds the adjacent portions of prongs 16 and 17 and is received within flange 51 and bears against the open top 12 of said receptacle 10. A securing element 29 extends through the cover plate and post 28 and secures said cover plate in position over the open top of said receptacle. The securing means may include a nut 31 positioned in recess 32 and threaded onto fastening means 29.

It will be noted that flange 51 provides a square seat to receive square cover plate 30 so that the cover plate may be positioned as shown in Figure 1 or the cover plate may be turned at right angles thereto so that the prongs 16 and 17 would extend transversely of passage 25. This arrangement is of material advantage since the cord may extend in different directions from the prongs 16 and 17. Thus, regardless of the position of the wall receptacle that receives the plug, the plug may be adjusted so that the cord may hang down or in any other desired position. The ledges 20 and 50 may receive the heads 18 and 19 of prongs

16 and 17 in positions corresponding to the position of cover 13.

From the foregoing description it will be apparent that the invention provides a construction in which the connector plug lies flat against the prong receiving receptacle, and need project from the surface thereof only for a distance equal to the smallest dimension of the plug. This dimension may be of the order of one half inch or less. It will also be apparent that, in the form of the invention shown in Figures 1, 2 and 3, the plug may be readily assembled or disassembled.

Obviously various modifications may be made from the embodiment of the invention described in the foregoing. The prongs 16 and 17 need not necessarily be constructed in the manner shown in Figure 4. For example, where desired, the prongs may be constructed from a single strip of suitable metal by crimping and bending the strip in the manner shown in Figure 5. Referring to this figure the prong 36 is formed of a strip of metal crimped intermediate its length at 37 and 38 to provide the prong and head or tab portions which correspond functionally with the prong and head or tab portions 16 and 18 respectively of Figure 4.

The connector plug need not necessarily be constructed in the manner shown in Figures 1, 2 and 3. Certain of the advantages of the invention may be obtained in a plug of the type in which the contact prongs are embedded in the molded insulating material, as shown in Figure 6. Referring to this figure the body of insulating material 40, which may, for example, be of soft rubber, has embedded therein the contact prongs 41 and 42. In this form of the invention the cable 43 is again disposed at right angles to the prongs. A pull of the cable does not readily disengage the plug from the socket. Again the plug body is relatively thin and flat and free from outward projections except the prongs, on either the receptacle face or the outer face of the plug.

Having thus described the invention what I claim is:

1. An electrical plug comprising a square shaped receptacle fabricated of insulating material and having its top open, a solid post fabricated of insulating material positioned within said receptacle substantially centrally thereof and having one end fixedly secured to the bottom of said receptacle, the other end of said post terminating at a point spaced inwardly from the open top of the receptacle, said post being cut away inwardly from the other end completely therearound to form a ledge, the bounding wall of said receptacle being cut away inwardly from the open top completely around said receptacle to form a second ledge, said first and second ledges being in alignment with each other, a first prong fabricated of conductive material having a flat head on one end positioned on one side of said post and extending through the open top of said receptacle and having its head resting against the adjacent portions of said first and second ledges, a second prong fabricated of conductive material having a flat head on one end positioned on the other side of said post and extending through the open top of said receptacle and having its head resting against the adjacent

portions of said first and second ledges, there being a passage extending inwardly from one of the sides of and in communication with said receptacle for receiving a cable, and a cover plate fabricated of insulating material surrounding the adjacent portions of said first and second named prongs and bearing against the open top of said receptacle and fixedly secured to the latter.

2. An electrical plug comprising a square shaped receptacle fabricated of insulating material and having its top open, a solid post fabricated of insulating material positioned within said receptacle substantially centrally thereof and having one end fixedly secured to the bottom of said receptacle, the other end of said post terminating at a point spaced inwardly from the open top of said receptacle, said post being cut away inwardly from the other end and completely therearound to form a ledge, the bounding wall of said receptacle being cut away inwardly from the open top completely around said receptacle to form a second ledge, said first and second ledges being in alignment with each other, a flange projecting from the bounding wall of said receptacle adjacent the open top and extending completely therearound, a first prong fabricated of conductive material having a flat head on one end positioned on one side of said post and extending through the open top of said receptacle and having its head resting against the adjacent portions of said first and second ledges, a second prong fabricated of conductive material having a flat head on one end positioned on the other side of said post and extending through the open top of said receptacle and having its head resting against the adjacent portions of said first and second ledges, there being a passage extending inwardly from one of the sides of and in communication with said receptacle for receiving a cable, a cover plate fabricated of insulating material surrounding the adjacent portions of said first and second named prongs received within said flange and bearing against the open top of said receptacle, and a securing element extending through said cover plate and post for securing said cover plate in position over the open top of said receptacle.
